UNITED STATES PATENT OFFICE.

JULIUS F. STONE, OF COLUMBUS, AND FRED MILLER, OF CORNING, OHIO.

PUMP.

SPECIFICATION forming part of Letters Patent No. 487,397, dated December 6, 1892.

Application filed April 7, 1892. Serial No. 428,216. (No model.)

To all whom it may concern:

Be it known that we, JULIUS F. STONE, residing at Columbus, Franklin county, and FRED MILLER, residing at Corning, Perry county, State of Ohio, citizens of the United States, have invented certain new and useful Improvements in Pumps; and we do hereby declare the following to be a full, clear, and exact description of the invention, such as will enable others skilled in the art to which it appertains to make and use the same.

The water and other fluids in mines is frequently mixed with powerful corrosives that soon destroy or render useless pumps of metal used in expelling it. As wood successfully resists the action of these deleterious substances, we have devised a pump especially adapted for use in mines, which are usually constructed almost wholly of that material.

The novelty in our case resides in the construction of valve-chamber for such pumps, substantially as hereinafter described and claimed.

In the accompanying drawings, Figure 1 illustrates a sectional view of the valve-chambers and pipes or water-ways connecting them. Fig. 2 illustrates a similar view of a pumping-engine, the pump-pistons, and suction-chambers. Fig. 3 illustrates a top plan view of one end of our pump, the parts being in operative position.

Like characters of reference in the different figures indicate corresponding parts.

The letter A designates the valve-chamber, which is constructed of three sections 1, 2, and 3, of wood. The lower section 1 is bored centrally to receive the short piece a of the induction-pipe. In boring this section a bridge 4 is left extending diametrically across the opening and in the direction of the grain of the wood to receive a pair of valves 5. The middle section 2 is made with a tapering passage or chamber and with a bridge like that in section 1, also to receive valves, as shown. The bore or opening of section 2 is made larger at its lower end, so as to allow room for the play of the valves 5 and afford a place on the surface of section 1 around the bore thereof for the reception of a metallic valve-seat 10. The lower surface of section 2 is rabbeted, as shown, and rests upon the metallic valve-seat and holds it in place. A port 9, the position

of which is shown by projection only in Fig. 1, is also made in the side of section 2. Section 3 of the valve-chamber is made with a cylindrical bore somewhat larger than the opening at the upper end of the bore of section 2, so that when section 3 is in position a place remains for an annular valve-seat 11, of metal or wood or composition. This valve-seat is held in position by the lower end of a tube E, of wood, which fits removably in the bore of section 3. The upper end of the chamber formed by the bore in section 3 is closed by a cover or lid held firmly in place by nuts on the ends of bolts 12, which pass vertically through section 3. The sections 1, 2, and 3, which compose the valve-chamber, are held securely together by bolts passing vertically through them. The sections are further strengthened by similar bolts passing horizontally through them. Washer-strips 13, of metal, may be placed under the nuts on the ends of the bolts.

In the drawings we have shown two valve-chambers alike in construction, one being a complement of the other, and they are supplied by a common induction-pipe 14, of wood. The upper or ejection compartments of the valve-chambers are connected by means of a wooden pipe 15 and a common outlet-pipe, as shown at 16. The pipe 15 has its ends rabbeted, as shown at 17, so as to afford a shoulder against which section 3 may abut and be tightly drawn by bolts 18, which extend from one chamber to the other.

The pumping-engine D is of usual construction. The plungers 6 work in suction-chambers C, made from cube-like blocks of wood bored centrally. Plates 7, which close the outer ends of the suction-chambers, and plates or heads 8, through which the plungers 6 pass, are secured in their respective places by means of bolts passing horizontally through the block constituting the suction-chamber. The pumping apparatus is given additional stability by bolts 19, (see Fig. 3,) passing through tubes 20 interposed between the plates 7 and heads 22 of the steam-cylinder.

The pumping-engine B and the suction-chambers C are secured by means of bolts or other suitable fastenings upon a bed D.

Ports 21 are made through the sides of the

suction-chambers C C, and the position and form of these ports are such that when the valve-chambers A are placed against the suction-chambers C, as shown in Fig. 3, they will be united and the pump ready for operation.

The working of the pump will be readily understood by those acquainted with the subject. The pipe 14 is connected with the water to be removed from the mine and upon the 10 operation of the engine the water is drawn (so to speak) into either valve-chamber and simultaneously forced out of the other into the ejection-compartments thereof and through the common outlet-pipe 16 to the surface of 15 the earth.

It will be obvious to those familiar with mining operations that the valve-chamber herein shown and described is of simple, cheap, and durable construction, that it will 20 successfully withstand the destructive action of mine-water, and that the parts most sub-

jected to wear may be readily taken apart and easily put together for repairs.

Having thus described our invention, what we claim, and desire to secure by Letters Patent, is—

In a pump of the kind described, a valve-chamber composed of superposed bored wooden sections 1 2 3, the section 3 having the removable tube E in its bore, a metallic valve-seat 10, resting upon the section 1 and held in position by the section 2, and a metallic valve-seat resting upon the section 2 and held in position by the removable tube E in the bore of the section 3, substantially as shown. 30 35

In testimony whereof we affix our signatures in presence of two witnesses.

JULIUS F. STONE.
FRED MILLER.
